UNITED STATES PATENT OFFICE.

WILLIAM PARKER STRAW, OF MANCHESTER, NEW HAMPSHIRE, ASSIGNOR TO DRAPER COMPANY, OF HOPEDALE, MASSACHUSETTS, A CORPORATION OF MAINE.

FEELER MECHANISM FOR LOOMS.

1,185,019.

Specification of Letters Patent. Patented May 30, 1916.

Application filed October 28, 1915. Serial No. 58,477.

To all whom it may concern:

Be it known that I, WILLIAM PARKER STRAW, a citizen of the United States, residing at Manchester, county of Hillsboro, 5 State of New Hampshire, have invented an Improvement in Feeler Mechanism for Looms, of which the following description, in connection with the accompanying drawing, is a specification, like characters on the 10 drawing representing like parts.

This invention relates to improvements in feeler mechanism for automatic filling replenishing looms and has for its primary object the production of a simplified form 15 of feeling mechanism adapted to coöperate with bobbins or other filling carriers having feeler slots to receive the end of the feeler when the last layer of filling is being unwound thereby causing the actuation of 20 the transferring means to replenish the shuttle with a full bobbin.

Another object of the invention is to provide means whereby automatic action of the transferring mechanism will be arrested 25 during the stoppage of the loom, so that the loom may be turned over by hand, while not running under power, without causing unnecessary transfer.

Other objects of the invention will more 30 fully appear from the following description and the accompanying drawings, and will be particularly pointed out in the annexed claims.

The invention is illustrated in the accompanying drawings as applied to the "Northrop" type of loom a sufficient portion of the loom being shown to disclose the relation of the novel elements and combinations thereto.

40 The drawings also show the manner in which these improvements may be incorporated in the "Northrop" type of loom without materially modifying the mechanism thereof.

45 In the drawings, Figure 1 is a plan view, centrally broken away of a portion of a loom embodying my invention; Fig. 2 is an elevation of the end portion of the loom, looking from the rear toward the front, 50 showing the manner in which the improved mechanisms are applied to the loom; Fig. 3 is a detail view, partly in section showing the latch which is connected to the controller rod and the means for actuating

the same from a vibrating actuator; Fig. 4 55 is a detail view of the novel feeler.

The mechanism illustrated herein is similar in many respects to that disclosed in my prior Patent No. 1,150,976 granted August 24, 1915 but comprising improvements 60 thereupon directed mainly to simplifications of structure which result in greater economy of construction and efficiency in operation. These improvements are illustrated herein as embodied in the well known "Northrop" 65 type of loom and are so constructed as to adapt the loom for the use of bobbins or other filling carriers having recesses or slots to receive the end of the feeler, as the last or nearly the last layer of filling is being 70 unwound and thereby initiate the action of the transfer mechanism to discharge the empty filling carrier and substitute a fresh one.

The loom illustrated in the drawings comprises the breast beam 1, the lay 2 with the shuttle boxes 3, 4 the hopper or battery 5 and transfer arm 6, the operation of the latter being effected through a controller (not shown) and controller rod 7 which may 80 be rocked upon detection of failure of filling either by the usual mechanism controlled and actuated by the weft fork 9 and weft hammer 10 or upon detection of substantial absence of filling by the feeler mechanism 85 which will hereinafter be described.

The feeler mechanism may conveniently be carried by the end or extension of the usual shipper plate 11. The feeler bracket 12 being preferably secured to the shipper 90 plate by a bolt 13 passing through slots 14, 15 disposed at right angles to each other in the feeler bracket and shipper plate respectively to permit both vertical and horizontal adjustment of the feeler. 95

The feeler preferably is in the form of a rod 16 having a reduced end portion 17 and is slidably mounted in a bearing in a lateral extension 18 of the feeler bracket 12 and in a bearing 19 in a supplemental 100 bracket 20 which may be secured to the bracket 12 by suitable screws or bolts 21. The feeler is provided with a collar 22 having a laterally projecting ledge 23 provided with a preferably V-shaped recess 24 in its 105 under face to engage the transmitter in a manner hereinafter to be described. The feeler is normally retained yieldably in ex-

- tended position by a helical spring 25 surrounding the rod 16 and bearing at its ends respectively upon the bearing 19 and the collar 22.
- 5 When the feeler is in normal extended position it is adapted to pass through the aperture 26 in the shuttle box, and the corresponding aperture 27 in the shuttle 28 and to engage the filling on the filling carrier 29 in the shuttle directly in alinement with the horizontal slot or recess 30 in the filling carrier so that the feeler will be forced forward against the force of the spring 25—
10 toward the front of the loom—upon each beat up of the lay so long as there is one or more layers of filling upon the filling carrier. When however the filling is sufficiently wound off to permit the end of the feeler to enter the recess or slot in the barrel
15 20 of the filling carrier the feeler will not be actuated but will be retained by its spring in the extended position shown in Figs. 1 and 4. When in such extended position the ledge 23 of the collar 22 lies directly over
25 the end of a transmitter 31, which preferably is in the form of a lever pivotally mounted upon a stud 32 projecting laterally from a bracket 33 which extends upwardly from the shipper stand.
- 30 The opposite end of the transmitter 31 preferably is provided with a substantially vertical extension 34 having laterally projecting ledges 35, 36 adapted to engage respectively the upper and lower faces of the
35 breast beam and thereby limit the movement of the transmitter 31. The vertical extension 34 desirably is also provided with a longitudinal projection 37 which is adapted to be engaged by a spring actuated dog carried
40 by the weft hammer or some other vibrating actuator, which moves in synchronism with the movement of the lay.
- In order to keep the dog engaging portion
45 50 55 60 65 70 75 80 85 90 95 100 105 110 115 120 125 130 of the transmitter extension 34 in elevated position the outer portion of the transmitter 31 is provided with a preferably integral counterweight 38. The dog 40 which engages the transmitter extension 37 preferably is pivotally mounted upon a stud 41 projecting laterally from an extension 42 of the weft hammer 43, being conveniently secured thereon by a bolt 44. The dog 40 is provided with a downwardly extending tail 40° between which and a ledge 45 on the
55 60 65 70 75 80 85 90 95 100 105 110 115 120 125 130 weft hammer extension 42 a spring 46 is seated, said spring normally tending to retain the dog in depressed position. The dog 40 preferably lies directly beneath a latch 47 which is pivoted upon a stud 48 at the end of a vertical extension or arm 7° of the controller rod 7, the free end of the latch 47 extending beneath a guiding stud 49 on the weft hammer extension 42. The latch 47 desirably is reduced near its end
65 70 75 80 85 90 95 100 105 110 115 120 125 130 to provide a shoulder 50, preferably having

an inclined face, adapted to be engaged by the end of the dog 40.

When in the normal operation of the loom the lay beats up, the filling on the filling carrier engages the feeler and forces the same forward, removing the collar 22 and its ledge 23 from the vertical path of the outer end of the transmitter. As the weft hammer follows closely the movement of the lay the dog 40 engages the projection 37 on the opposite end of the transmitter and depresses it since the strength of the spring 46 is more than sufficient to overcome the counterweight 38.

When, however, the filling carrier becomes sufficiently unwound to permit the end 17 of the feeler 16 to enter the recess or slot 30 in the filling carrier the collar 22 and its ledge 23 are retained in the extended position illustrated in Figs. 1 and 4, and when the dog 40 engages the projection 37 at the opposite end of the transmitter the outer end of the transmitter 31 engages the recess 40 in the ledge 23 of the feeler collar 22 thus preventing further movement of the transmitter. Upon further forward movement thereupon of the weft hammer the dog 40 rides up on its curved under surface until its end engages the shoulder 50 of the latch 47, and upon still further movement rocks 95 the arm and the controller rod 7 sufficiently to cause the action of the transfer mechanism to replenish the exhausted shuttle.

As looms are often stopped either manually or automatically for the purpose of splicing the warp ends and for making adjustments or repairs, at which times the loom is frequently turned over by hand with the shuttle withdrawn or improperly boxed, it is desirable that the automatic action of the transfer mechanism be suspended to avoid unnecessary transfer. This may be accomplished in the present construction by a very simple expedient consisting of co-operating means carried by the shipper lever and the transmitter adapted to lock the latter in inoperative position during the stoppage of the loom.

As illustrated herein the shipper lever 51, which is of the usual type pivotally mounted on a bracket 52 carried by the loom frame, is provided with a laterally extending stud 53, which may have a surrounding anti-friction collar 54, adapted to engage the under inclined face of the counterweight 38, and lift the same to inoperative position.

In order to avoid the necessity of accurate construction and also to prevent injury in case the shipper should be thrown while the feeler is in extended position and the ledge 23 overlying the end of the transmitter, the under face of the counterweight 38 preferably is provided with a recess 55 and a spring plate 56 is secured over the same, to be engaged by the stud on the shipper. In 180

the normal operation of the loom however the shipper will seldom if ever be actuated to stop the loom and to engage the transmitter when the latter is prevented from movement by the ledge on the feeler.

It will be readily understood by those skilled in the art that the mechanism described herein may be varied widely within the scope of my invention, for example the 10 stud may be located upon the transmitter and the yielding coöperating member may be carried by the shipper, or intermediate mechanisms may be introduced to effect the same result. It should also be understood 15 that the embodiment of the invention disclosed herein is illustrative thereof and is not restrictive of the following claims.

Having fully described my invention, what I claim as new and desire to secure by 20 Letters Patent is:

1. In an automatic filling replenishing loom equipped with filling carriers having feeling recesses, transferring mechanism, controlling mechanism therefor including a 25 controller rockshaft and latch, a vibrating actuator, a spring actuated dog carried thereby, a transmitter engaged by said dog upon each forward movement of said actuator, a spring actuated feeler having a laterally extended ledge adapted upon entry of the end of the feeler into the feeling recess in a filling carrier to engage the end of said transmitter and to restrain the movement thereof and thereby cause said dog to engage and actuate the controller latch to initiate the action of the transfer mechanism.

2. In an automatic filling replenishing loom comprising transferring mechanism, feeler mechanism, a vibrating actuator, a 40 transmitter operable by said feeler mechanism upon detection of substantial exhaustion of filling to initiate the action of the transferring mechanism, stop mechanism including a shipper and coöperating means 45 carried respectively by said shipper and said transmitter adapted to prevent automatic action of the transferring mechanism during the stoppage of the loom.

3. In an automatic filling replenishing 50 loom comprising transferring mechanism, feeler mechanism, a vibrating actuator and a transmitter operable by said feeler mechanism upon detection of substantial exhaustion of filling to initiate the action of the

transferring mechanism, stop mechanism 55 including a shipper, a stud on said shipper positioned to engage and raise said transmitter when the shipper is thrown to stopping position, and thereby prevent automatic action of the transferring mechanism 60 during the stoppage of the loom.

4. In an automatic filling replenishing loom comprising transferring mechanism, feeler mechanism, a vibrating actuator and a transmitter operable by said feeler mechanism upon detection of substantial exhaustion of filling to initiate the action of the transferring mechanism, stop mechanism including a shipper, a stud on said shipper, and a yieldable member on said transmitter 65 70 adapted to be engaged thereby when the shipper is thrown to stopping position whereby automatic action of the transferring mechanism will be avoided during the 75 stoppage of the loom.

5. In an automatic filling replenishing loom comprising transferring mechanism, feeler mechanism, a vibrating actuator and a counterweighted transmitter operable by said feeler mechanism upon substantial exhaustion of filling to initiate the action of the transferring mechanism, stop mechanism including a shipper, and a stud upon said shipper positioned to engage and raise the transmitter to inoperative position as 80 85 the shipper is thrown to stopping position, thereby preventing the automatic action of the transfer mechanism during the stoppage of the loom.

6. In an automatic filling replenishing loom comprising transferring mechanism, feeler mechanism, a vibrating actuator, a pivoted transmitter having an integral counterweight provided with a yieldable member operable by said feeler mechanism 90 95 upon detection of substantial exhaustion of filling to initiate the action of the transferring mechanism, stop mechanism including a shipper and a stud on said shipper adapted to engage the yieldable member upon said counterweight when the shipper is thrown to stopping position whereby the action of the transferring mechanism will be avoided during the stoppage of the loom.

In testimony whereof, I have signed my 100 name to this specification.

WILLIAM PARKER STRAW.
